ATTORNEY

UNITED STATES PATENT OFFICE.

WALTHER C. RUHLANDT, OF JACKSON, MICHIGAN.

VALVE AND VALVE-SEAT FACING TOOL.

Application filed February 16, 1921. Serial No. 445,428.

To all whom it may concern:

Be it known that I, WALTHER C. RUHLANDT, a citizen of the United States, residing at Jackson, in the county of Jackson and

5 State of Michigan, have invented certain new and useful Improvements in Valves and Valve-Seat Facing Tools, of which the following is a specification, reference being had to the accompanying drawings.

10 This invention relates to improvements in valve and valve seat facing tools.

An important object of the invention is to provide a device of this character whereby the valve may be surfaced while in position 15 in its guide, and whereby in one continuous operation the valve may be surfaced and the seat likewise surfaced, thus assuring proper alinement of the valve surface with the stem of the valve and with the seat.

20 A further object of the invention is to provide in combination with a cutter member adapted to surface both the valve and the seat, means whereby the valve may be rotated in the cutter member independently 25 of the cutter member, and means whereby the valve and cutter member may be simultaneously rotated.

A further object of the invention is to provide a novel-construction of cutting member comprising a frusto-conical shell having formed in the side walls thereof, slots, the material of the slots being disposed at an angle to the shell to form facing members, alternate facing members being directed 30 inwardly and outwardly so that the shell is provided upon its outer face with facing members for surfacing a valve seat, and upon its inner face for surfacing the valve.

35 Other objects and advantages of the invention will become apparent throughout the course of the following description.

In the accompanying drawings, wherein for the purpose of illustration are shown preferred embodiments of my invention, and 40 wherein like reference characters designate like parts throughout,

45 Figure 1 is a side elevation partly in section showing my device applied for surfacing the valve, the operating member being disposed to rotate the valve independently of the shell,

50 Figure 2 is a side elevation of the shell detached,

55 Figure 3 is a bottom plan view of the shell,

Figure 4 is a bottom plan view of a slightly modified form of shell,

Figure 5 is an edge elevation of the operating member, and

Figure 6 is a view similar to that shown in Figure 1, the operating member being arranged to simultaneously rotate the valve and shell.

Referring now more particularly to the drawings, the numeral 10 indicates a frusto-conical shell, the shell having formed in the edge of the large end thereof, diametrically opposed notches 10^a. The shell has formed therein, slots 11, extending radially when viewed in plan, and the metal of the shell normally forming these notches is struck inwardly and outwardly to form inner facing or cutting members 13 and outer facing or cutting members 12. In the forms shown in Figures 2 and 3 the facing members are formed in each side of the slot, one being directed inwardly and the other outwardly, and in the form shown in Figure 4 the metal of the slots is alternately struck inwardly and outwardly to form the facing members. These facing members have their edges parallel.

50 In the employment of the shell the valve 14 is inserted in the shell with the stem 15 of the valve projecting through the open smaller end of the shell and the shell is then inverted and placed upon the valve seat 16, the stem of the valve entering its guide 55 15^a.

60 An operating member for rotating the valve and the valve and shell is provided comprising a body portion 17 squared or otherwise adapted at its outer end for engagement with the driving element whereby it may be rotated. The lower end of the body portion 17 is furcated to form spaced arms 19 between which is rotatably mounted a substantially rectangular plate 20 having opposed short sides 20^a and long sides 20^b.

65 As is well known to those familiar with the art, valves in the construction thereof are provided in their heads with means whereby they may be rotated, this means sometimes taking the form of a centrally disposed slot and at other times taking the form of a pair of spaced recesses adapted for the reception of lugs upon the driving member. In order that the driver or operating member may be adapted for engage-

ment with all of these types of valves, I provide upon one of the short sides 20^a of the plate a tongue 21 adapted to engage in groove-headed valves, and upon the other of the short sides 20^a are formed lugs 22 adapted to engage in the sockets of socket-headed valves. The short side of the plate is not of sufficient width to span the base or wide end of the shell and accordingly when either the tongue 21 or lugs 22 of the short sides 20^a are in engagement with a valve, the shell is not engaged and the valve may be rotated independently of the shell.

In order that the valve and shell may be simultaneously rotated with the valve in position, the long sides of the plate 20 are provided, one with a tongue 21 and the other with lugs 22. When a long side of the plate 20 is presented for engagement with the valve, the ends of the plate extend through the notches 10^a of the shell and accordingly the valve and shell are simultaneously rotated. It will be seen that by placing the valve in the shell and entering the valve stem in its guide so that the exterior of the shell is engaging the valve seat and the operating face of the valve is engaging the abrading members of the interior of the shell, the operating member 17 may first be employed to rotate the valve within the shell so as to surface the valve and the plate 20 may be rotated to bring the corresponding long side of the plate into engagement with the valve and shell, and the shell and valve simultaneously rotated to surface the seat. This continuity of operation is particularly advantageous in that it insures proper alinement of the valve with its seat and in that the shell being maintained in alinement by the valve and the valve having its stem in engagement with its guide, the seat formed will be in proper alinement with the valve guide.

From the foregoing it is believed to be obvious that I have provided a valve seat and valve surfacing device which is particularly well adapted for use by reason of the simplicity of its structure, the facility with which it may be operated and the cheapness with which it may be manufactured.

It will furthermore be obvious that the structure as hereinabove set forth is capable of some change in modification without materially departing from the spirit of my invention, and I accordingly do not limit myself to such specific structure except as hereinafter claimed.

What I claim is:

1. In a tool for facing valves and valve seats, a shell provided interiorly with facing members for facing a valve, and exteriorly with facing members for facing a valve seat, said shell having notches formed in the edge of one end thereof, and a driving member embodying portions adapted to engage

a valve disposed within the shell to rotate the same independently of the shell, and other portions adapted to simultaneously engage the valve and the notches of the shell to simultaneously rotate the valve and shell. 70

2. In a tool for facing valves and valve seats, a shell provided interiorly with facing members for facing a valve and exteriorly with facing members for facing a valve seat, a driving member comprising a body portion at one end for engagement with means whereby it may be connected to a source of rotation, a plate pivotally mounted in the lower end of said body portion, and embodying portions adapted to engage a valve disposed within a shell to rotate the same independently of the shell and other portions adapted to simultaneously engage the valve and shell to simultaneously rotate the same. 80 85

3. In a tool for facing valves and valve seats, a frusto-conical shell having slots formed therein, each of said slots being provided at an edge thereof with a portion disposed at an angle to the shell and forming a facing member, alternate facing members being inwardly and outwardly directed. 90

4. In a tool for facing valves and valve seats, a frusto-conical shell having slots therein directed radially of the shell when the shell is viewed in plan, the metal of the shell at the longitudinal edges of the slots being bent at an angle thereto and forming facing members, the facing member at one side of each of the slots being inwardly directed and the facing member at the other side being outwardly directed. 100 105

5. In a tool for facing valves and valve seats, a shell having slots therein, said slots being provided at the edge thereof with a portion disposed at an angle to the shell and forming a facing member, alternate facing members being inwardly and outwardly directed, the working faces of said facing members being arranged upon concentric conical surfaces. 110

6. In a tool for facing valves and valve seats, a shell having slots therein extending substantially longitudinally of the shell, the metal of the shell at the longitudinal edges of the slots being bent at an angle thereto and forming facing members, the facing member at one side of each of the slots being inwardly directed, and the facing member at the other side being outwardly directed. 115 120

7. In a tool for facing valves and valve seats, a shell provided interiorly with facing members for facing the valve and exteriorly with facing members for facing the valve seat, said shell having notches formed in an end thereof and a driving member adapted at one end for engagement with means whereby it may be connected to a source of rotation, a plate pivotally mounted in the lower end of said body portion and 125 130

substantially rectangular in form, said plate being provided upon the ends thereof with portions for engaging valves of different structures when the same are disposed with-

5 in the shell to rotate the same independently of the shell and upon the sides thereof with portions for engaging valves of different structures when disposed within the shell,

and with other portions adapted to simultaneously engage the shell in the notches 10 thereof whereby to simultaneously rotate the valve and shell.

In testimony whereof I hereunto affix my signature.

WALTHER C. RUHLANDT.
